(57) CLAIM

The ornamental design for a display screen with animated graphical user interface, as shown and described.

DESCRIPTION

FIG. 1 is a first image in a sequence of a display screen with animated graphical user interface showing our new design according to a first embodiment;

FIG. 2 is a second image thereof;

FIG. 3 is a first image in a sequence of a display screen with animated graphical user interface showing our new design according to a second embodiment;

FIG. 4 is a second image thereof;

FIG. 5 is a first image in a sequence of a display screen with animated graphical user interface showing our new design according to a third embodiment; and,

FIG. 6 is a second image thereof.

The outermost broken lines showing a display device illustrate environmental subject matter, whereas the broken lines showing a display screen and elements of the animated

graphical user interface illustrate portions of the article. No subject matter depicted in broken lines forms part of the claimed design.

Grey shading, patterning, or the appearance thereof included in at least the claimed portions of FIGS. 1-6 are illustrative of contrast, and are not representative of any particular color, shade, or patterning.

The appearance of the animated graphical user interface sequentially transitions between the images shown in FIGS. 1-2, 3-4, and 5-6. The process or period in which one image transitions to another image forms no part of the claimed design.
